UNITED STATES PATENT OFFICE.

CATHARINE COOPER HUNGERFORD, OF WATERTOWN, NEW YORK.

HAIR-DRIER.

SPECIFICATION forming part of Letters Patent No. 674,418, dated May 21, 1901.

Application filed February 16, 1901. Serial No. 47,302. (No model.)

To all whom it may concern:

Be it known that I, CATHARINE COOPER HUNGERFORD, a citizen of the United States, residing at Watertown, in the county of Jefferson and State of New York, have invented certain new and useful Improvements in Hair-Driers, of which the following is a specification.

My invention relates to that class of driers for use in drying women's hair after washing or shampooing.

The objects of the invention are to provide a simple, efficient, and durable drier for the purpose described; to provide an adjustable neck-rest just below the drying-plate; to make said drying-plate in two separable sections for storage and shipping purposes; to provide means for adjustably supporting the standard to allow for vertical and lateral adjustment; to provide a separable supporting means for the drying-plate adapted for connection with an ordinary chair-back, and to provide a simple heating attachment. These objects I accomplish by the mechanism shown in the accompanying drawings, in which—

Figure 1 is a perspective view of my improved hair-drier with one-half of the hair supporting screen or plate removed and indicated by dotted lines. Fig. 2 is a plan showing the under side of the hair-supporting screen. Fig. 3 is a section on line $x-x$ of Fig. 1 looking in the direction of arrows. Fig. 4 is a detail section on line $y-y$ of Fig. 1 looking in the same direction. Fig. 5 is a detail tail of a portion of hair-supporting screen showing actual nature of perforations. Fig. 6 is a detail showing parts of upper end of the main standard or rod. Fig. 6^a is a plan of the socket A^3 . Fig. 7 is a side elevation of clamp by which the drier may be secured to chair-back. Fig. 7^a is a perspective of said clamp. Fig. 8 is a detail plan view of yoke or rest for supporting the person's head or neck. Fig. 9 is a plan of support for radial ribs, and Fig. 10 is a vertical sectional view of what is shown in Fig. 9.

A designates the vertically-adjustable main supporting-standard, provided with a base A' , having a set-screw a , by means of which the standard may be set at any adjusted height, or in lieu of this support A' the support shown in Figs. 7 and 7^a may be employed, as will be

hereinafter fully described. The upper end of the standard A is provided with a bifurcated block or head A^2 , in which is pivoted at a^2 the vertically-rocking socket A^3 .

Below the head A^2 is mounted the vertically-adjustable rib-supporting collar or sleeve B , provided with an angle-flange B' , having a number of radial slots b .

C designates the radial supporting-arms for the drying-screen D . These arms C have their inner ends curved downward and provided near the lower ends of such curved portions with transverse pins or projections c , which rest on the flange B' and support the ribs C in the slots b , as clearly shown in Figs. 1, 9, and 10. The collar or sleeve B is provided with a set-screw B^2 , Fig. 9, by means of which it may be set at any desired height. The drying-screen D is formed, preferably, of a perforated plate in two halves or sections D' D^2 , having a tongue-and-groove connection along their adjacent edges, as shown in Fig. 4, where the two sections are separated for clearness. The sections D' D^2 have a marginal strengthening-flange, the flange d' on the section being formed with a groove d^3 to receive the adjacent flanged edge d^2 of the section D^2 , and the section D' is further provided with set-screws d^4 to engage the flange d^2 and hold the two sections securely together in the position shown in Fig. 2. The drying-screen is also provided at the inner end of the flange d' with a depending attaching-pin d^5 , which enters the aperture in socket A^3 , as shown in Fig. 1.

The drying-screen D is recessed at d^6 for the neck of the person and is provided around its entire margin, at its under side, with a series of curtain-hooks d^7 , on which the curtain E is suspended. As the screen D is free to rock, owing to its pivoted socket A^3 , it may be given any desired angle of adjustment by simply raising or lowering the sleeve B and its connected arms C , and in order that the head and neck of the person may be properly supported regardless of the adjustment of the screw, I provide a neck or head rest F , (see Figs. 1 and 6,) adapted to engage the back of the neck and provided with parallel slotted arms f^f , which embrace the head A^2 , to which they are adjustably held by two set-screws f^f' , carried by the head. By these

screws the rest F may be secured after being longitudinally adjusted, and the rest is further supported on a vertical adjusting-screw f^2 , mounted in an arm f^3 , projecting from the head A². It will be seen, therefore, that the head of the person may be supported in a perfectly comfortable position regardless of the angle of the screen D.

G is a simple form of heater mounted on the standard A; but any source of heat or any suitable drying medium, such as air, may be employed under the screen.

H designates a clamp or support for securing the standard A (see Figs. 7 and 7^a) in place to the back of a chair occupied by the person whose hair is to be dried. This clamp or support comprises a cross-bar H', having a central aperture through which the standard A passes and is held by a set-screw h, the ends of the cross-bar passing through the bends of two U-shaped clamps h' h' and provided exterior thereto with thumb-nuts h², by means of which the cross-bar may be held against turning in the clamps. The clamps are provided, as usual, in one of their depending legs with horizontal clamping-screws h³ h³ to engage the chair-back and hold the parts in place thereon.

The operation is as follows: The occupant is seated in a chair, the rest F and screen D are properly adjusted, and the hair is spread out over the screen D. The ascending currents of air, preferably heated air, will now pass through the screen and the hair and quickly and thoroughly dry the latter.

After the operation is finished the screen may be removed, taken apart, and folded, and so also with the radial arms and supporting-standard. The device will now occupy but small space and may be easily stored in any convenient place.

The hair-supporting screen may be formed of foraminated sheet-metal plates, woven wire, or other suitable material, and by the term "screen" I mean any perforated or intersticed material through which the air may ascend.

Having thus described my invention, what I claim, and desire to secure by Letters Patent, is—

1. A hair-drier, comprising a standard provided at its upper end with a horizontally-disposed foraminated or reticulated plate, on top of which the hair may be spread; the lower side of the plate being uninclosed, and a fabric-curtain suspended from the margin of the said plate to direct ascending air-currents therethrough.

2. A hair-drier, comprising a standard provided at its upper end with a horizontally-disposed hair-supporting screen, means for adjusting the screen to an angle or incline and a curtain depending from the screen.

3. In a hair-drier, a standard provided with vertically-adjustable radial arms and a hair-supporting screen pivoted to the standard and supported therebeyond on said arms.

4. In a hair-drier, a standard provided with a vertically-adjustable sleeve or collar, a plurality of radial arms carried by the sleeve or collar, and a hair-supporting screen pivoted to the upper end of the standard and supported therebeyond by said radial arms. 70

5. In a hair-drier, a standard provided with a vertically-adjustable flanged sleeve or collar 75 having radial slots, a series of arms curved downward at their inner ends and there provided with transverse pins or projections for holding the arms in the slots, a socket pivoted to the upper end of the standard, and a hair-supporting screen mounted on said socket and supported therebeyond by said arms. 80

6. In a hair-drier, a standard provided at its upper end with a removable sectional hair-supporting screen, curtain-suspending devices around the margin of the screen, and means for adjusting the screen to an angle or incline. 85

7. In a hair-drier, a standard provided at its upper end with a removable sectional two-part hair-supporting screen, a tongue-and-groove joint connecting the adjacent edges of the sections and means for fastening or securing said edges together. 90

8. In a hair-drier, a standard provided at its upper end with a socket, a hair-supporting screen formed in two separable sections one of which is provided with a pin to enter said socket. 100

9. In a hair-drier, a hair-supporting screen in two sections, a groove in one section receiving the edge of the other section, and set-screws to bind the two sections of the screen together. 105

10. In a hair-drier, a hair-supporting screen in two sections, a groove in one section receiving the adjacent edge of the other section, set-screws to bind the sections together, an attaching-pin on one section and curtain-supporting devices on said sections. 110

11. In a hair-drier, the combination with a standard, of a hair-supporting screen on the upper end thereof, and a neck or head rest secured to the standard adjacent to one edge 115 of the screen and separate and independent thereof.

12. In a hair-drier, the combination with a standard, and an adjustable hair-supporting screen, of an adjustable neck or head rest on the standard adjacent to one edge of the screen. 120

13. In a hair-drier, the combination with a standard and an adjustable hair-supporting screen pivotally connected with the upper end 125 of the standard, adjustable radial arms for supporting the screen beyond the standard, and a head or neck rest having arms adjustably connected to the standard below the screen and a vertical adjusting-screw on 130 which the neck-rest is supported beyond the standard.

14. The combination with the standard and the hair-supporting screen, of a support com-

prising a clamp to embrace a chair-back or like device and means for adjusting the standard on the clamp.

15. The combination with the standard and the hair-supporting screen, of a support comprising two clamps adapted to engage a chair-back and provided with an adjustable cross-bar having an aperture for the standard and a set-screw to bind the standard therein.

10 16. A hair-drier comprising, a standard or support, provided at its upper end with a hair-

supporting screen formed of a foraminated or reticulated plate, a curtain suspended from the margin of the screen, means for adjusting the screen at an angle and a heater mounted on the standard within the curtain. 15

In testimony whereof I affix my signature in presence of two witnesses.
